UNITED STATES PATENT OFFICE

DEAN C. SEITZ, OF CLEVELAND, OHIO, ASSIGNOR TO THE RUSS MANUFACTURING COMPANY, A CORPORATION OF OHIO

DESIGN FOR A DRAFT ARM FOR A SODA FOUNTAIN

Application filed July 12, 1930. Serial No. 36,338. Term of patent 7 years.

To all whom it may concern:

Be it known that I, DEAN C. SEITZ, a citizen of the United States, residing at Cleveland, in the county of Cuyahoga and State of Ohio, have invented a new, original, and ornamental Design for a Draft Arm for a Soda Fountain, of which the following is a specification, reference being had to the accompanying drawing, forming a part thereof.

In the drawing:

Figure 1 is a side elevation of a draft arm for a soda fountain showing my new design;

Fig. 2 is a rear elevation of a draft arm for a soda fountain showing my new design; and

Fig. 3 is a plan view of a draft arm for a soda fountain showing my new design.

I claim:

The ornamental design for a draft arm for a soda fountain, as shown.

DEAN C. SEITZ.
